UNITED STATES PATENT OFFICE.

JOHN W. FREE, OF WOODLAWN, PENNSYLVANIA, ASSIGNOR TO JONES & LAUGHLIN STEEL COMPANY, OF PITTSBURGH, PENNSYLVANIA, A CORPORATION OF PENNSYLVANIA.

MILL FOR COLD-ROLLING SKELP.

1,374,145.

Specification of Letters Patent.

Patented Apr. 5, 1921.

Application filed March 11, 1920. Serial No. 365,009.

To all whom it may concern:

Be it known that I, JOHN W. FREE, residing at Woodlawn, in the county of Beaver and State of Pennsylvania, a citizen of the 5 United States, have invented or discovered certain new and useful Improvements in Mills for Cold-Rolling Skelp, of which improvements the following is a specification.

My invention relates to improvements in 10 mills for shaping pipe skelp preparatory to welding, and, more particularly, to mills for shaping such material while cold, and bringing it to tubular form with overlapped edges, ready for lap-welding. The objects 15 are simplicity and effectiveness.

My invention is embodied in a mill illustrated in the accompanying drawings. Figure I is a view of the mill in side elevation; Fig. II is a view of it in plan; Fig. III is 20 a vertical transverse section, on the plane indicated by the line III—III, Fig. I; Fig. IV is a view in elevation of one of the pairs of rolls detached; and Fig. V is a fragmentary view to a larger scale, showing in elevation one of the guides for the material in its advance from one roll pass to another. Figs. VI to XII inclusive show in vertical section the successive roll passes through 25 which the material in the course of its fabrication passes, and associated with the rolls themselves the material is shown. Above the successive roll passes of the mill as shown in Figs. I and II I have placed the numerals VI, VII, VIII, etc., thus indicating to which roll pass each sectional view 30 belongs.

The mill consists essentially of a succession of pairs of rolls, forming the succession of roll passes illustrated in Figs. VI to XII, 40 inclusive. In Fig. II I have applied the numerals 1 to 7 to the upper rolls there shown of this succession of pairs.

These rolls, it will be observed, are arranged all of them in parallel positions—in 45 this instance they are all horizontal, and this arrangement makes possible the mounting of them all in a common frame or housing 8 and the driving of them, or at least so many of them as are power driven, 50 through the gear train 9 of simple arrange-

ment, sufficiently indicated in Figs. I, II, and III. The intervals at which the successive roll pairs are set are conveniently short, and the mill accordingly becomes a continuous mill (there is no appreciable 55 elongation of the material under treatment). Ordinarily, a single length of material under treatment will in the course of treatment be engaged by all or substantially all of the shaping rolls simultaneously. 60

Between successive roll pairs are arranged suitable guiding means, including the idle beveled rollers 10 mounted on vertical stub shafts and placed in pairs between the passes. One of these guide rollers is illustrated in Fig. V and their positions are indicated in Figs. I and II. 65

At the delivery end of the mill straightening means are provided, and these preferably include a pair of rollers 11, which ordinarily need have no capacity for relative movement, but which are mounted to rotate idly in their bearings. Their faces are properly shaped, and of a shape which will be more clearly defined in the sequel. This 70 pair of rollers is, in order to accomplish its intended ends, mounted for adjustment as a unit, both vertically and horizontally. 75

Coming now to the skelp-shaping instrumentalities and their operation, the development of a skelp into a pipe blank will be 80 sufficiently understood on careful consideration of Figs. VI to XII, with reference to the other figures to make plain the roll-driving means.

First of all, it is to be observed that a flat skelp is developed by transverse bending into a tubular blank with overlapped edges: a blank of proper shape and size, and with edges sufficiently overlapped, to undergo 90 the welding operation and produce a lap-weld pipe of the intended dimensions. The bending of the blank is developed by beginning with the skelp in horizontal plane and arching it upward. The blank as it develops is accordingly downwardly concave, and, by virtue of this position, it clears itself 95 of scale between the roll passes.

Coming to particular definition of the roll passes, the preferred arrangement is as fol- 100

lows: the rolls of the first pass are shaped to develop a uniform curvature, across the width of the skelp; in the second pass, the radius of the side portions of the now curved blank is diminished to a smaller dimension than the middle portion. At the same time, however, the middle portion also is preferably reduced somewhat in curvature. In the third pass the curvature of the mid portion is reduced and the whole brought to uniform curvature, preferably to the curvature of the side portions in the second pass; in the fourth pass the radius of the bottom of the now trough-shaped blank, the middle portion of the blank, is still further reduced. The lower roll of the fourth pass is the last one to engage the inner surface of the developing blank; both rolls of the fifth pass engage the exterior surface, for the curvature of the blank has now, as will be seen in Fig. IX, developed until the angular sweep of the arc which the blank forms, exceeds 180°. In the fifth pass the radius is reduced throughout and made substantially uniform, the two edges of the blank coming now into close proximity. The lower roll of the sixth pass is stepped, and in the sixth pass one edge of the blank is bent inward a distance as great as the thickness of the material, and this portion is thus brought to substantially its ultimate curvature; otherwise, there is no reduction of curvature in the sixth pass. The seventh pass constricts the tubular blank to its ultimate dimensions, and brings the edges to the desired overlapped position.

All the roll pairs are preferably positively driven, excepting only the sixth, the pair which effects the depression of one edge relatively to the other. I find it preferable to avoid a frictional tension of roll upon blank here; but instead mount the rolls of this pair for idle turning.

I desire to call attention to the fact that all of the instrumentalities which act upon the material while in the course of formation to tubular shape ready for lap welding act upon it externally; there is no internal ball nor mandrel upon which the developing tube is shaped. This is a great simplification and, while my instrumentalities do not forbid the use of such a ball or mandrel, I consider its absence a distinct and substantial advantage, and it is a thing not known before in the preparation of blanks for lap welding.

I desire further to note that the shaping instrumentalities engage and exert shaping stress upon and only upon the faces of the skelp, leaving the scarfed edges free of stress, free of shaping contact with roll surfaces or with one another, and so unmutilated and undamaged for the ultimate welding operation.

No claim is here made to the method of

bending skelp which is herein disclosed, such method being the subject of an application for Letters Patent filed by me August 24th, 1920, Serial No. 405,758. In the application referred to my invention *in re* method is claimed by myself as subject matter for Letters Patent.

In the ensuing claims I define the essential features of my invention, leaving the mechanism in other respects subject to adaptation, as the engineer may prefer. The showing of the drawings is in those respects exemplary merely.

I claim as my invention:

1. A skelp-bending mill wherein the shaping instrumentalities consist only and entirely of a plurality of pairs of rolls, shaped to engage the skelp upon its faces only and in such engagement to shape to a tubular blank with overlapped edges ready for lap-welding a length of skelp with scarfed edges. 80

2. A skelp-bending mill wherein the shaping instrumentalities consist only and entirely of a plurality of pairs of rolls all mounted with parallel axes, shaped to engage the skelp upon its faces only and in 90 such engagement by cold rolling to shape to a tubular blank with overlapped edges ready for lap-welding a length of skelp with scarfed edges.

3. A skelp-bending mill wherein the shaping instrumentalities consist only and entirely of a succession of pairs of rolls shaped to engage pair by pair the skelp, one of the rolls of one of the pairs other than the last having a stepped rolling face, and the rolls 100 of the next succeeding pair, engaging the developing blank upon its external surface only, being shaped and proportioned to constrict the blank to the form of a tube with overlapped edges. 105

4. A mill for bending skelp by cold-rolling wherein the shaping instrumentalities consist only and entirely of seven pairs of rolls, shaped to engage the skelp upon its faces and in such engagement to shape to a 110 tubular blank with overlapped edges a length of skelp with scarfed edges, the roll passes between the pairs of rolls possessing successively the following characteristics: first, a pass in which the skelp is bent transversely 115 to a curve of uniform radius; second, a pass in which the curvature of the side portions is reduced in radius and reduced in greater degree than the medial portion; third, a pass in which the curvature of the medial portion is further reduced and made of equal radius with the side portions; fourth, a pass in which the curvature of the medial portion is reduced in radius, while that of the side portions continues unchanged; fifth, a pass 125 in which the curvature of the side portions is reduced and made equal in radius with that of the medial portion; sixth, a pass in

which one edge is pressed inward relatively to the other and reduced in radius of curvature; and, seventh, a pass wherein the remainder of the article is reduced in radius of curvature.

5 5. A mill wherein a length of skelp is by cold-rolling brought to the shape of a tube with overlapped edges, ready for lap-welding, such mill consisting of a plurality of

pairs of rolls, mounted all on parallel axes, 10 the upper roll of each pair being concave.

In testimony whereof I have hereunto set my hand.

JOHN W. FREE.
